G. W. Edgcomb,

Washing Machine,

No 12,658,

Patented Apr. 3, 1855.

Fig. 1.

Fig. 2.

UNITED STATES PATENT OFFICE.

GEORGE W. EDGCOMB, OF LIMA, INDIANA.

WASHING-MACHINE.

Specification of Letters Patent No. 12,658, dated April 3, 1855.

To all whom it may concern:

Be it known that I, GEORGE W. EDGCOMB, of the town of Lima and county of La-
5 grange, in the State of Indiana, have in-
vited a new and Improved Washing-Ma-
chine; and I do hereby declare that the fol-
lowing is a full and exact description there-
of, reference being had to the accompanying
10 drawings, making a part of this specifi-
cation, Figure 1 being a top view of the tub
with the rubbing-disk removed; Fig. 2, a
vertical transverse section through the cen-
ter of the washing-machine and Fig. 3 a sec-
15 tion in the line P P of Fig. 2.

Similar letters indicate parts in all
the figures.

The nature of my invention consists in the
peculiar arrangement of correspondingly
20 shaped rubbers O, and I, placed on the bot-
tom H, of the tub, and on the under side of
the rubbing disk G, between which the
clothes are to be washed; viz: The rubbers
25 are of a half round tapering shape, with
rounded ends, and are secured upon the bot-
tom of the tub, and upon the under side of
the disk G, in alternating radial positions,
the broad end of one being placed between
30 two narrow ends of the others, and vice-
versa, as shown in the drawings.

I make use of a round tub, which may be
made in any well known or usual manner.
The bottom H, of the tub should be of suffi-
cient strength to firmly support the stand-
ard L; the disk G, is suspended to the oper-
35 ating lever M, by means of the legs K, K.
The operating lever M, is steadied by means
of an aperture in its center, which is received
upon an elongated journal at the upper end
of the standard L. The disk G, is lifted
40 from the tub, to allow the clothes to be
washed, to be placed in the tub; then, after
supplying the requisite quantity of soap and
water, the disk is returned to its place in
the tub, and a reciprocating or a rotary mo-
45 tion is imparted to it until the clothes have
been sufficiently acted upon.

The effect of the alternating arrangement
50 of each series of the tapering rubbers O, I,
is to keep the clothes in such a position that
they will be constantly and efficiently acted
upon by the rubbers, and prevent them from
being crowded against the sides, or into the
center of the tub. The faces of the broad
ends of the ribs, secured to the vibrating

or rotating disk G, are placed so as to barely
55 clear coming in contact with the faces of the
broad ends of the ribs on the bottom of the
tub,—as will be perceived by the drawings.

Now it is self evident, that as the disk G,
is rotated, when the face of the large end
60 of one of its ribs O, passes over the large
end of a rib I, on the bottom of the tub,
the clothes will be forced toward the smaller
ends of the two ribs at the same time that
they are forced forward, and that the next
65 action upon the clothing will be between
the parallel surfaces of the said moving
rib O, and the next rib I, in succession,
caused by the large end of the said rib O,
being brought over the smallest end of a
70 rib I; and that the next action upon the
clothing will be caused by the large end of
the said rib O, being brought over the large
end of a rib I, which will force the clothing
75 toward the smaller ends of the said ribs,
and in an opposite direction to the action
first above mentioned. Thus it will be seen,
that the clothing will first be thrown out-
ward, by the large end of a moving rib
80 coming over the large end of a stationary
rib, then be acted upon by the parallel sur-
faces of a moving rib and a stationary rib,
as the large end of the moving rib comes
85 next over the small end of a stationary rib,
and then the said clothing will be thrown
inward when the large end of the said mov-
ing rib comes over the large end of the next
stationary rib in succession;—making three
90 different and distinct kinds of action upon
the clothing.

I am aware that a wash-board has been
made of a conical form, having its surface
higher above the bottom of the tub at the
circumference than at the center, with radial
95 ribs, of the form of a half cone, attached
to it and to the bottom of the tub, with their
broadest ends outward, and with spaces be-
tween them of such width and depth as to
receive the clothes between them in such a
100 manner as to turn them over, has been used
before in the washing machines of Joel Wis-
ner, patented November 8th, 1853, and there-
fore I do not claim such as my invention,
for the reason that I deem that I have made
105 a marked improvement thereon; and there-
fore

What I do claim as my invention and de-
sire to secure by Letters Patent, is—

The alternating radial arrangement of the tapering rubbers O, and I, upon the under side of the actuating disk G, and upon the bottom H, of the tub, substantially in the 5 manner and for the purpose herein set forth.

The above specification of my improve-

ment in washing machines signed and witnessed this 17th day of October, 1854.

GEORGE W. EDGCOMB. [L. s.]
